UNITED STATES PATENT OFFICE.

JAMES W. CLAXTON, OF ABILENE, TEXAS.

DESIGN FOR A GRAVE MARKER.

Application filed November 28, 1925. Serial No. 15,574. Term of patent 3½ years.

To all whom it may concern:

Be it known that I, JAMES W. CLAXTON, a citizen of the United States, residing at Abilene, county of Taylor, and State of Texas, have invented a new, original, and ornamental Design for a Grave Marker, of which the following is a specification, reference being had to the accompanying drawing, which shows a perspective view of the marker showing my new design.

I claim:

The ornamental design for a grave marker as shown.

JAMES W. CLAXTON.
